(57) **CLAIM**

The ornamental design for a cell imager, as shown and described.

DESCRIPTION

FIG. 1 is a top perspective view of the cell imager;
FIG. 2 is a bottom perspective view of the cell imager;
FIG. 3 is a front view of the cell imager;
FIG. 4 is a rear view of cell imager;
FIG. 5 is a first side view of the cell imager;
FIG. 6 is a second view of the cell imager;
FIG. 7 is a top view of the cell imager;
FIG. 8 is a bottom view of the cell imager; and,
FIG. 9 is a top perspective view of the cell imager with a flask positioned in place on the imager.
The broken lines depict the flask in FIG. 9 represent an environment, and the remaining broken lines represent portions of the cell imager that form no part of the claimed design; the broken lines form no part of the claimed design.

1 Claim, 8 Drawing Sheets
